DESIGN FOR A BLOUSE

Benjamin Shander, Philadelphia, Pa.

Application August 3, 1940, Serial No. 94,227

Term of patent 3½ years

To all whom it may concern:

Be it known that I, Benjamin Shander, a citizen of the United States, residing in Philadelphia, in the county of Philadelphia and State of Pennsylvania, have invented a new, original, and ornamental Design for a Blouse, of which the following is a specification, reference being had to the accompanying drawing, forming part thereof.

Fig. 1 is a front view of a blouse showing my design, and

Fig. 2 is the rear view thereof.

I claim:

The ornamental design for a blouse, substantially as shown.

BENJAMIN SHANDER.
